Primary Examiner — Caron D Veynar*Assistant Examiner* — Martie K Holtje(74) *Attorney, Agent, or Firm* — Hayes Soloway P.C.(57) **CLAIM**

The ornamental design for a single space parking meter, as shown and described.

DESCRIPTION

FIG. 1 is a top, left front perspective view of a single space parking meter showing our new design;

FIG. 2 is a top, right rear perspective view thereof;

FIG. 3 is a left side elevational view thereof;

FIG. 4 is a front elevational view thereof;

FIG. 5 is a right side elevational view thereof;

FIG. 6 is a rear elevational view thereof; and,

FIG. 7 is a top plan view thereof.

The structural elements depicted by broken lines have been shown for the purpose of illustrating portions of the single space parking meter that form no part of the claimed design.
